UNITED STATES PATENT OFFICE

2,100,674

CONVERTIBLE HOIST

Frank E. Stahl, Tonawanda, N. Y., assignor to
Columbus McKinnon Chain Corporation, Tonawanda, N. Y., a corporation of New York

Application July 6, 1935, Serial No. 30,181

1 Claim. (Cl. 254—169)

My invention relates generally to hoists and more particularly to a detachable pin for a movable hoist block.

My invention is particularly applicable to a hoist having a single chain with a load hook at the lower end thereof. It is sometimes desirable to increase the capacity of such a hoist and my invention provides a movable hoist block which may be used in connection with the chain of the hoist to increase its capacity without having to disturb the regular hook supplied at the end of the hoist chain. In order that such a device be useful, however, it is essential that it be possible to attach the same to the load chain of the hoist 15 without having to disturb the hook regularly supplied with the chain.

One of the principal objects of my invention has been to provide a convertible hoist having a movable, load engaging, hoist block so designed that it may be easily engaged with or removed 20 from the loop formed in the hoist chain.

Another object has been to provide the hoist with means for detachably receiving a part of the load chain near the load hook thereof so as to 25 provide a loop for the reception of the movable block.

Moreover, the hoist block of my invention is so arranged that, while the movable block pin may be easily removed, it is prevented from accidental 30 displacement.

The above objects and advantages have been accomplished by the device shown in the accompanying drawing, of which:

Fig. 1 shows a side view of my improved hoist.

Fig. 2 is an enlarged, sectional view showing the movable hoist block thereof.

Fig. 3 is an enlarged, side view of the chain hook of my hoist.

Fig. 4 is a face view of the same.

In the drawing I have shown a gear type hoist which is actuated by means of a ratchet lever but, obviously, the invention is just as advantageously employed in connection with a hoist having a hand chain.

In the drawing, 5 represents the hoist and 6 the ratchet lever for operating the same. The hoist is provided with a casing 7 which encloses the gears (not shown). The chain engaging member 8 is carried by the casing. This chain hook 50 is formed with a longitudinal recess 9 on each side of which is a lug 10 having a pocket 11 formed therein for the reception of two adjacent chain links.

In the drawing, 12 is the regular, single load 55 chain of the hoist which is provided at its lower

end with the regular permanently attached hook 13 and swivel 14. When the capacity of my hoist is to be increased, sufficient chain is run through the hoist to make a depending loop therein, and a number of links adjacent the swivel 14 are engaged with the chain engaging member 8 so as to detachably hold a part of the chain near the load hook end thereof. 5

A load-engaging block 20, forming part of my invention, is now engaged with the loop in the 10 load chain, as shown in Fig. 2. This block comprises a frame or yoke 21 to which is pivotally attached a load hook 22. A chain wheel 23 is pivotally carried by the yoke 21 of the block and is mounted upon a pin 24. In order to make my 15 hoist easily convertible, it must be possible to quickly and easily remove the pin 24 of the chain wheel so that such wheel may be placed in detachable engagement with that part of the load chain of the hoist which forms the loop, as just 20 above described. In order to have the pin removable, I provide an annular groove 25 near its outer end and make the length of the pin somewhat shorter than the distance between the faces 26 and 27 of the frame. The pin is provided with a head 28 which bears against the surface 26 and limits its inward movement. A 25 plunger 29 is slidably mounted in a bore 30 formed in one of the arms of the frame 21 and this plunger is provided with a rounded inner end 31. A flange 32 is also provided on the plunger which engages with a shoulder 33 formed by an enlarged bore 34. The flange 32 of the plunger engaging with this shoulder limits the inward 30 movement of the plunger for reasons to be hereinafter described. A helical spring 35 is mounted in the bore 34 and a screw 36 is mounted in the outer end of the bore, serving to retain the spring in its adjusted position. The walls of the groove 25 and the end 31 of the plunger are so 35 formed that by striking the inner end 37 of the pin, the groove 25 may be disengaged from the plunger, which will be moved inwardly against the tension of the spring 35, and permit the pin to be removed from the frame and from the wheel, whereupon, the wheel may be removed 40 from the frame and placed in the loop formed for it in the load chain. When the pin is removed, the flange 32 will engage the shoulder 33 and prevent the plunger from being pushed out of the bore 30. After the wheel is placed in the loop and engaged with the chain, the frame is then 45 engaged with the wheel and the pin 24 is again passed through the openings formed for it in the frame and is driven to place by being tapped on 50 55

the head 28. The end 37 of the pin is provided with a chamfer 38 which engages with the end 31 of the plunger 29 and serves to depress the same sufficiently to allow the end 37 to pass by it, whereupon, when the groove 25 registers with the plunger, the plunger will be pressed upwardly by means of the spring 35 and engaged with the groove. Since the end 37 does not extend to the surface 21, it will be obvious that the pin cannot be driven from its position by being accidentally struck.

It will be obvious from the foregoing that the hoist may be easily converted from one capacity to another without having to disturb any permanent fastening means, it being only necessary to drive out the pin 24, either to disconnect the wheel 23 from the pin or to attach it thereto, and to hook or unhook the links near the load hook 13 of the chain hoist.

While I have shown and described my invention as applied to a chain hoist, it is obvious that by slight changes, within the scope of my invention, it may be adapted for use on a cable hoist.

These and other modifications of the details herein shown and described may be made without departing from the spirit of my invention or the scope of the appended claim, and I do not, therefore, wish to be limited to the exact embodiment of the invention as herein shown and described.

Having thus described my invention, what I claim is:

A convertible hoist, comprising a casing, a single load chain having a load hook permanently secured to the end thereof, a chain engaging member carried by the casing for detachably receiving a part of the chain near the load hook thereof, whereby, when so engaged, a depending loop is formed in the chain, and a movable load engaging block engageable with the loop, comprising a frame, a load engaging hook carried by the frame, a pin carried by the frame, spring-pressed means for retaining the pin in detachable position, and a chain wheel pivotally mounted on the pin.

FRANK E. STAHL.
